UNITED STATES PATENT OFFICE

GEORGE S. BLAKESLEE, DECEASED, LATE OF OAK PARK, ILLINOIS, BY GEORGE R. BLAKESLEE, EXECUTOR, OF OAK PARK, ILLINOIS, AND GEORGE P. ANSTISS, OF OAK PARK, ILLINOIS, ASSIGNORS TO G. S. BLAKESLEE & CO., OF CICERO, ILLINOIS, A CORPORATION OF ILLINOIS

DISH HOLDING BASKET

Original application filed August 2, 1923, Serial No. 655,241. Divided and this application filed March 28, 1925. Serial No. 19,019.

This invention relates to dish holding baskets of the type commonly employed in dish washing machines in which the baskets are moved through the machine over the wash water contained in a tank below the path of said baskets, meanwhile water from the tank being thrown on the dishes supported in the baskets by means of a paddle wheel which dips into the water in the tank and throws the water forcibly against the dishes. This application is divisional of the copending application of George S. Blakeslee and George P. Anstiss, Serial No. 655,241, filed August 2, 1923, now Patent No. 1,712,728, granted May 14, 1929, wherein this general type of dish-washing machine is disclosed. The present invention has for its object to provide an improved dish supporting rack for such baskets which may be made entirely of wood, and which will be substantial in construction and of such design as to receive dishes of various shapes and hold them securely in place and in the proper position for the application of the wash water thereto while they are being washed, thereby not only reducing the danger of breakage, but also insuring the proper cleansing of the dishes. Such object is accomplished as illustrated in the drawings and hereinafter more particularly described.

What we regard as new is set forth in the claims.

In the drawings,

Fig. 1 is a plan view of a dish washing machine basket equipped with the improved rack;

Fig. 2 is a longitudinal vertical section on line 2—2 of Fig. 1;

Fig. 3 is an enlarged perspective view illustrating some details of the construction of the rack; and

Fig. 4 is an enlarged perspective view of one of the upright fingers which form a part of the rack.

Referring to the drawings,—5 indicates a basket such as is designed to receive and support the improved rack, said basket being preferably rectangular in form as shown, and made of sheet metal. The dishes to be washed are supported in said basket by means of a wooden rack, indicated as a whole by the ref-

erence numeral 6, comprising a plurality of longitudinally-disposed wooden bars 7 suitably spaced apart as shown, and held in fixed relation to each other by means of a series of cross-rods 8, also made of wood, which are fitted in transverse holes 9 in the bars 7. By this construction a reticulated framework is formed by the longitudinally extending bars 7 and the cross-rods 8 which is entirely of wood so that there is less danger of breakage should the dishes be carelessly deposited on the rack than if the parts were of metal.

The bars 7 are spaced apart the proper distance to receive between them cups or similar articles, and the cross-rods 8 are also spaced properly to support such articles, as best illustrated in Fig. 1. As also shown in said figure, large plates are supported by two adjacent longitudinal bars 7, and, as will be apparent, other smaller dishes, or dishes of irregular shape, may be supported either by single bars or by several.

For the purpose of supporting plates and other relatively flat dishes in an approximately vertical position, the longitudinally extending bars 7 are provided with upwardly extending wooden pins or fingers 10, rectangular in cross section and provided with square tenons 11 that are driven into round holes 12 which extend through the bars 7 from the top downward. These holes 12 in the bars 7 are preferably formed slightly inclined from the vertical, as illustrated in Fig. 2, and the abutting portions of the fingers 10 and bars 7 are arranged to contact or abut squarely, as shown in said figure, to provide a firmer support for said fingers. This is best accomplished by sloping or inclining the upper surfaces of said bars around the holes 12 so that they are perpendicular to the axes of said holes, and providing the fingers with perpendicular shoulders 10^a at the bases of the tenons 11. By providing the fingers 10 with the square tenons and driving them into the round holes 12 as above described, the fingers are firmly secured in place, as the corners of the tenons cut into the bars to some extent and are wedged tightly in place. The shoulders 10^a contact tightly with the upper surfaces of the bars over said holes so that the

95
100

fingers 10 are held firmly against deflection as well as against rotation.

The sloping surfaces around the holes 12 are extended downward beyond said holes far enough so that the shoulders formed by cutting down the bars 7 to form such sloping surfaces, together with the sloping surfaces, provide notches 13 resembling troughs in the upper surfaces of each of the bars 7 back of each of the fingers 10 to receive the edges of saucers, plates and the like, as shown in Fig. 2, and the upper portions of the fingers 10 cooperate with said notches or troughs to secure the dishes firmly so that they are not liable to be displaced by the wash water, which is thrown forcibly upon them by the paddle wheel.

The basket 5 is provided with inwardly-projecting flanges 14 at the ends thereof, as shown in Fig. 1, on which flanges the ends of the bars 7 rest, and, if desired, the rack 6 may be secured in the basket by driving nails 15 through its ends into the ends of said bars, as shown by dotted lines in Figure 2. Such nailing may, however, be dispensed with if it be preferred that the rack be more readily removable.

This invention provides a dish supporting rack which securely and safely supports dishes of a variety of sizes and shapes so that they will not easily be displaced by the force of the wash water thrown on them by the paddle wheels, and which may be made entirely of wood, thereby reducing the danger of breakage.

While the basket shown and described is primarily intended for use in connection with dish washing machines of the type described, it may, of course, be used with any other kind of dish washing machine to which it is adapted.

What we claim as the invention of said GEORGE S. BLAKESLEE, deceased, and GEORGE P. ANSTISS, and desire to secure by Letters Patent, is—

1. A dish holding rack for dish washing machines comprising parallel horizontal wooden bars provided with round holes therein at intervals and inclined to the vertical, the upper surfaces of said bars around said holes being at right angle to the axis of said holes, a series of fingers carried by said bars, said fingers having square tenons at their lower ends inserted in said holes, and having shoulders perpendicular to the bases of said tenons abutting against said inclined surfaces, and means for spacing said bars apart.

2. A dish holding rack for dish washing machines comprising a plurality of substantially parallel bars spaced apart, and a series of substantially parallel upwardly extending fingers carried by said bars and spaced apart longitudinally thereof, said bars having transverse notches narrower than the

spaces between the bottoms of said fingers disposed between adjacent fingers to receive the edges of plates and like dishes resting against said fingers.

3. A dish holding rack for dish washing machines comprising parallel wooden bars provided with round holes therein at intervals, a series of substantially upright fingers carried by said bars and having square tenons at their lower ends and shoulders perpendicular to the tenons, said tenons being driven into the holes and the shoulders abutting squarely against the upper surface of the bars, and means for spacing the bars apart.

4. A dish holding rack for dish washing machines comprising parallel bars spaced apart and provided with notches at intervals along their upper edges, and a series of upwardly extending fingers carried by said bars projecting from within the notches, said notches being narrower than the spaces between the bottoms of said fingers for positioning the edges of plates and like dishes and said fingers in each next adjacent notch bracing the dishes at an angle for washing purposes.

5. A dish holding rack for dish washing machines comprising parallel bars spaced apart and provided with notches at intervals along their upper edges, said notches comprising surfaces inclined to the horizontal intersecting substantially vertical surfaces, the latter forming the shoulder portions of the notches, a series of upwardly extending fingers carried by said bars projecting substantially at right angles to the inclined surfaces of the notches thereon, said fingers being spaced away from the shoulders of the notches and extending across the full width of said bars to form troughs traversing the bars, said troughs coacting with the fingers in each preceding notch for positioning and bracing the plates or like dishes.
